UNITED STATES PATENT OFFICE.

HERMANN G. DITTBENNER, OF MINNEAPOLIS, MINNESOTA.

CUSHION FOR LOG-CARRIAGES.

SPECIFICATION forming part of Letters Patent No. 760,854, dated May 24, 1904.

Application filed January 11, 1904. Serial No. 188,479. (No model.)

To all whom it may concern:

Be it known that I, HERMANN G. DITTBENNER, a citizen of the United States of America, residing at Minneapolis, in the county of 5 Hennepin and State of Minnesota, have invented certain new and useful Improvements in Cushions for Log-Carriages; and I do hereby declare the following to be a full, clear, and exact description of the invention, such as will 10 enable others skilled in the art to which it appertains to make and use the same.

My present invention is especially directed to an improved arrangement of cushions for log-carriages; and to the above end the invention 15 consists in the novel arrangement thereof hereinafter described, and defined in the claim.

As is well known, log-carriages are of very strong and heavy construction, and their 20 frames involve longitudinal side beams that extend from end to end of the carriage and are tied together at their ends and elsewhere by transverse timbers. Hitherto it has been customary to arrange a cushion at each end 25 of the track on which the carriage moves in such position that they will engage the central portions of the transverse end timbers. With this arrangement the great strain thrown upon the engaged transverse end timbers has 30 in practice frequently broken the same, and sometimes when not broken they have been known to yield and permit the carriage to jump over the cushion, thus doing all sorts of damage.

In accordance with my invention I arrange 35 the cushions in pairs and secure the same in such positions that one will be directly engaged by the end of each alined side beam of the carriage. In this way the strain due to 40 the stopping of the carriage is directly thrown endwise upon the unyielding side beams. In other words, the said side beams receive the stopping force with a direct endwise thrust.

The invention is illustrated in the single 45 view of the drawing, which is a plan view with some parts broken away.

In the said drawing the numeral 1 indicates the rails of the track on which the carriage moves, the said rails, as shown, being rigidly 50 secured to heavy floor-timbers 2.

Of the parts of the carriage it is only nec-

essary to note the wheels 3, axles 4, and the frame made up of the longitudinally-extended side beams 5 and transverse end timbers 6.

The cushions, which may be of any approved 55 form, are preferably made up of cylinders or dash-pots 7 and pistons 8, the stems of which project for contact with the ends of the side beams 5. These cylinders or dash-pots 7 are, as shown, rigidly secured to heavy transverse 60 timbers 9, that are rigidly secured to the ends of the timbers 2. It will be noted that the cushions are located with their axes directly in line with the side beams 5 of the carriage, so that the projecting ends of the said beams 65 at a given end of the carriage will simultaneously be thrown into engagement with the projecting ends of the stems of the pistons 8 for an important purpose, which has already been stated. By the statement that the ends 70 of the beams 5 directly engage the ends of the piston-stems it is not meant that the ends of the wooden bodies of the said beams actually contact with the ends of the piston-stems, for, on the contrary, in practice the ends of 75 the said beams would advisably be faced with metal caps to prevent the same from being split or pounded out of shape.

The gist of this invention is found in the arrangement of the cushion with respect to 80 the carriage so that all strains put upon the carriage when the same is run against the cushions are resisted by an endwise thrust or blow received directly in line with the side beams of the carriage.

What I claim, and desire to secure by Letters Patent of the United States, is as follows:

The combination with a track and a carriage movable over the same, said carriage having longitudinally-extended side beams, of 90 a pair of cushions anchored with respect to the track and located one in line with each side beam of said carriage, whereby strains, in stopping the carriage, are received directly by and endwise of the said side beams, substantially as described.

In testimony whereof I have affixed my signature in presence of two witnesses.

HERMANN G. DITTBENNER.
